UNITED STATES PATENT OFFICE.

SAMUEL J. SHARP, OF WHEELING, WEST VIRGINIA.

DESIGN FOR AN EASEL.

SPECIFICATION forming part of Design No. 31,452, dated August 22, 1899.

Application filed September 24, 1898. Serial No. 691,824. Term of patent 3½ years.

To all whom it may concern:

Be it known that I, SAMUEL JAMES SHARP, a citizen of the United States of America, and a resident of Wheeling, county of Ohio, and 5 State of West Virginia, have invented and produced a new and original Design for Easels and Analogous Articles, of which the following is a specification, reference being had to the accompanying drawings, forming a part 10 thereof.

Figure 1 is a plan view of the easel, showing my new design. Fig. 2 is a sectional view taken on the line X X of Fig. 1.

As shown in the drawings, the design consists of a metal sheet the lower part of which 15 is heart or shield shaped and has upon its face the figure of a skull and cross-bones, said figure presenting a raised or convex surface on the face of the shield. On the top of said shield is a 20 helmet 1 with closed beaver, upon which rests the figure of a bird 2. At each of the upper

corners of the shield is the head of a battle-
ax 3, the handles of which appear to extend
diagonally across the back of or behind the
shield, thus crossing each other. The butts 4 25
of the handles extend below the shield and
serve as legs or supports upon which the body
of the easel rests. The whole is composed of
one sheet of metal, the different figures thereon
each presenting a convex surface. 30

Having thus described my invention, what
I claim is new, and desire to secure by Letters
Patent, is—

The design for an easel herein shown and
described. 35

In testimony whereof I have hereunto af-
fixed my signature in the presence of two
witnesses.

SAML. J. SHARP.
